UNITED STATES PATENT OFFICE.

SILAS B. RUSSELL, OF ST. LOUIS, MISSOURI, ASSIGNOR TO PARKER-RUSSELL MINING & MANUFACTURING COMPANY, OF ST. LOUIS, MISSOURI, A CORPORATION OF MISSOURI.

RETORT-DISCHARGING APPARATUS.

Application filed November 22, 1920. Serial No. 425,775.

To all whom it may concern:

Be it known that I, SILAS B. RUSSELL, a citizen of the United States, residing at St. Louis, Missouri, have invented a certain new and useful Improvement in Retort-Discharging Apparatus, of which the following is a full, clear, and exact description, such as will enable others skilled in the art to which it appertains to make and use the same.

This invention relates to apparatus of the kind that are used in connection with through retorts or open-ended retorts for dislodging or discharging the material from such retorts. It relates particularly to retort discharging devices of the kind which comprise a ram or pushing device that is adapted to be introduced endwise into the rear end of a through retort, and means for enabling said ram to be raised and lowered so as to bring it into alignment with any one of a plurality of tiers of retorts arranged at different levels.

The main object of my invention is to provide a retort discharging apparatus of the general type just referred to which is so constructed that the mechanism used for moving the ram or pusher into and out of the retorts does not move vertically with the ram when the level of the ram is changed to bring it into alignment with the retorts of the different tiers, thereby making it possible to materially reduce the weight of the apparatus and simplify the construction of same and also overcome the necessity of having the operator in charge of the apparatus ride on a part that is raised or lowered when the level of the ram is changed.

Another object of my invention is to provide a discharging device for open-ended retorts which is of such design that it is particularly adapted for use in connection with inclined retorts, and furthermore, can be operated easily by hand power. Other objects and desirable features of my invention will be hereinafter pointed out.

To this end I have devised a retort discharging apparatus, which, briefly described, consists of a supporting structure arranged at one side of a bench of open-ended retorts and capable of being moved longitudinally of the bench, a carriage mounted on said supporting structure and adapted to be moved towards and away from the rear ends of the retorts in a direction parallel to the

longitudinal axis of the retorts, a ram or pusher carried by the carriage and adapted to be introduced into the retorts so as to dislodge the material in the retorts or discharge said material through the front ends of the retorts, means for enabling the level of said ram or pusher to be varied so as to bring it into alignment with the retorts of the different tiers, and an operating mechanism for said carriage mounted on a part of said supporting structure that is stationary with respect to the carriage and the ram. In the form of my invention herein illustrated said supporting structure is suspended from a truck that travels on an overhead track and the ram or pusher is carried by a shiftable member that slides vertically in a frame or guideway that depends from the carriage. Said vertically-movable member is counterbalanced so that it can be easily raised and lowered to bring the ram or pusher into alignment with a particular tier of the bench of retorts, and the mechanism for actuating the carriage preferably consists of a cable or similar device and a winding drum and a counterweight mechanism combined with said winding drum in such a manner that very little power is required to turn the drum to actuate the carriage, and moreover, the carriage will remain at rest when the operating pressure is removed from the winding drum, even though the track on which the carriage travels is inclined, as is necessary when the apparatus is designed for use with inclined retorts. I wish it to be understood, however, that the particular construction and method of operating the supporting structure is immaterial; that the ram or pusher can be mounted on the carriage in various other ways and that various other means than that herein illustrated can be employed for actuating the carriage without departing from the spirit of my invention.

Figure 1 of the drawings is a side elevational view of a retort discharging apparatus constructed in accordance with my invention.

Figure 2 is an end view of said apparatus, looking from one end of same towards the rear ends of the retorts.

Figure 3 is a detail view of the ram or pusher illustrating the locking device that is used for holding the extensible section of the ram in its extended position.

Figures 4 and 5 are cross-sectional views, taken on the lines 4-4 and 5-5, respectively, of Figure 3; and

- Figure 6 is a detail view of one of the locking devices on the supporting structure of the apparatus that is used for holding the extensible section of the ram at rest when the carriage is being moved to telescope the two sections of the ram.
- 10 Referring to the drawings which illustrate the preferred form of my invention, A designates the supporting structure of my improved apparatus which is preferably built up principally of commercially rolled shapes such as channel irons, and A' designates a movable truck traveling on an overhead track from which the supporting structure A is suspended, said truck being so arranged that the supporting structure A can be moved longitudinally of a bench of retorts composed of a plurality of tiers of retorts π . It is immaterial what form of truck is used for carrying the supporting structure A, and in some forms of apparatus I prefer 25 to mount the supporting structure A on the truck of a charging lorry. The apparatus herein illustrated is designed for use with inclined, open-ended retorts, and therefore, the supporting structure A is shown as being provided with an inclined track B arranged in parallel relation to the longitudinal axes of the retorts, so as to form a runway for a carriage C provided with a ram or pusher C' that is adapted to be introduced endwise into 30 the rear ends of the retorts so as to dislodge the material therein or discharge the contents of the retorts. When the apparatus is designed for use with horizontal retorts the track B will, of course, be arranged in a horizontal position. Moreover, while I have 35 illustrated the supporting structure A as being suspended from an overhead truck, I wish it to be understood that it is immaterial, so far as my invention is concerned, 40 how said structure is mounted, so long as it can be shifted longitudinally of the bench of retorts. In order to steady the supporting structure A it is preferable to provide the lower end portion of said supporting 45 structure with a roller 1, as shown in Figure 1, that bears against the curb 2 of the floor 2^a on which the operator in charge of the apparatus stands.
- The inclined track B previously referred 50 to is preferably formed by two channels arranged opposite to each other in parallel relation with the flanges of the respective channels projecting towards each other, as shown in the upper portion of Figure 2.
- 55 The carriage C, which may be of any preferred form and construction, is provided with wheels or rollers 3 which are of such diameter that they will fit snugly enough between the flanges on the track B to prevent 60 the carriage C from tilting during the dis-

charging operation and loose enough to insure said carriage moving freely. The carriage C is moved towards and away from the retorts by a mechanism which preferably consists of a winding drum D (see Figure 2) 70 and a cable 4 secured to the upper end of the carriage C and extending from same over a sheave 5 carried by a bracket on the upper end of the track B, downwardly from said sheave 5 to an idler drum or sheave 6 carried by a bracket on the lower part of the supporting structure A, under said sheave 6 and around the drum D, thence upwardly from said drum over a sheave 7 mounted on the upper end portion of the track B, downwardly from the sheave 7 around a sheave 8 arranged adjacent the lower end of the track B, and thence upwardly from the sheave 8 to the lower end of the carriage C, as shown clearly in Figure 1. The winding drum D 80 is rigidly connected to a horizontally-disposed shaft 9 mounted in bearings on the lower part of the supporting structure A, and a means of any preferred type or construction is provided for rotating said drum 85 in one direction, so as to cause the carriage C to move downwardly towards the retorts and to rotate said drum in the opposite direction so as to move said carriage upwardly back to its normal position. In the apparatus herein illustrated a manually operated means is employed for turning the drum D, which means consists of a horizontally-disposed shaft 10 arranged in parallel relation to the shaft 9 in bearings on the lower part 95 of the supporting structure A, a hand wheel 11 on the front end of the shaft 10 for turning same, and a pinion 12 on the shaft 10 (shown in dotted lines in Figure 1) which meshes with a gear 13 on the drum shaft 9. 100 The hand wheel 11 is so disposed that it can be operated conveniently by a workman standing on the floor 2^a. While I prefer to use a hand operated mechanism for actuating the carriage C, I wish it to be understood 105 that any other suitable means could be used for actuating said carriage without departing from the spirit of my invention. A counterweight mechanism is preferably combined with the operating mechanism for the carriage C so as to make it possible for a single workman to move said carriage back and forth on its track B and also to insure 110 said carriage remaining at rest in any position on an inclined track such as the track B 115 when pressure is removed from the hand wheel 11 of the carriage operating mechanism. One form of counterweight mechanism that I have found to be well adapted for this purpose consists of a weight G connected to the lower end of a cable or other suitable device 14 which leads upwardly from said weight over a sheave 15 supported by the track B, and thence downwardly to a drum 16 that is rigidly connected to the 120

125

130

drum shaft 9 to which the winding drum D is connected.

The ram or pusher C' is mounted on the carriage C in such a manner that said ram can be raised and lowered relatively to said carriage so as to bring the ram into alignment with the retorts of the different tiers. As shown in Figure 1, the carriage C is provided with a depending frame E that forms a guideway for a vertically-movable member F which carries the ram C', said frame or guideway E being preferably formed by four vertically-disposed angle bars connected together by crossed bars or strips so as to form a rigid guideway for the vertically-adjustable member F. The member F may be of any preferred construction and the ram C' can be mounted on said member F in various ways. I prefer to counterweight the member F so as to enable said member to be moved easily upwardly and downwardly so as to bring the ram C' into alignment with the top, intermediate or bottom tier of retorts, the counterweight herein shown consisting of a weight 17 that is connected to the lower end of a cable 18 or other suitable device which leads upwardly from the weight over sheaves 19 on the underside of the carriage C and thence downwardly to a part of the ram that is rigidly connected to the vertically-movable member F, as shown in Figure 1.

The ram or pusher of the apparatus is preferably constructed in such a manner that the length of same can be increased easily so as to make said ram long enough to extend clear through the retorts. In the form of my invention herein shown said ram comprises a stationary portion 20 rigidly connected at its upper end to the vertically-movable member F, and an extensible portion 21 to which the head of the ram is connected. The stationary portion 20 of the ram can be formed conveniently by two angle irons arranged back to back and rigidly connected together so as to form a substantially inverted T-shaped member, as shown in Figures 4 and 5, and the extensible portion 21 of the ram can be formed conveniently by a pipe or rod arranged on the underside of the stationary portion 20 of the ram and slidably mounted in a bearing 22 connected to the lower end of said stationary portion 20. The extensible portion 21 of the ram is provided at its upper end with a part 23 that is slidably mounted on the stationary portion 20 of the ram, said part 23 being rigidly connected to the extensible portion 21 and provided with slots that receive the laterally-projecting flanges on the stationary portion 20 of the ram, as shown more clearly in Figure 5. To increase the length of the ram it is only necessary to move the extensible portion 21 downwardly longitudinally of the stationary portion 20 of

the ram, the parts 22 and 23 co-operating with the two portions of the ram to hold said portions in substantially parallel relation. Various means may be used for locking the extensible section 21 of the ram in its extended or retracted position, the means herein shown for this purpose consisting of oscillating latches 24 and 25 mounted in bearings on the stationary section 20 of the ram. When the extensible section 21 is retracted, as shown in Figure 1, the latch 24 engages the part 23 at the upper end of said extensible section and holds said section in its retracted position, and when the section 21 is extended, the latch 25 engages said part 23, as shown in Figure 3.

In order to facilitate the operation of extending or retracting the extensible section 21 of the ram the supporting structure A of the apparatus is provided with a plurality of holding devices 26 consisting of bolts or similar elements arranged on said supporting structure at points in approximate alignment with the different tiers of retorts and adapted to co-operate with a member 27 on the extreme upper end of the extensible portion 21 of the ram, which is provided with a hole 28, as shown in Figure 1.

When it is desired to dislodge or discharge the material from one of the retorts in the upper tier the supporting structure A is shifted longitudinally of the bench so as to bring the ram into vertical alignment with the retort which is to be discharged and the vertically-movable member F which carries the ram is then moved upwardly into its highest position, as shown in Figure 1, so as to bring the head on the ram into longitudinal alignment with said upper retort. The operator in charge of the apparatus who stands on the floor 2^a then turns the hand wheel 11 in a direction to cause the carriage C to move downwardly or towards the retort. When said carriage reaches the lower end of the track B, as shown in dotted lines in Figure 1, the operator first trips the latch 24 so as to release the extensible section 21 of the ram and he then moves the upper bolt or holding device 26 on the supporting structure A in such a direction that the end of said bolt will project into the hole 28 in the head 27 on the extensible section of the ram, thus securely locking said extensible section to the supporting structure A. The hand wheel 11 is then turned in the opposite direction so as to move the carriage C upwardly on the track B. In view of the fact that the extensible section 21 of the ram is locked to the supporting structure A, said extensible section will remain at rest while the carriage C is moving upwardly, but the section 20 of the ram will move with the carriage, owing to the fact that said section 20 is rigidly connected to the member 130

which is arranged in the depending frame E on the carriage. By the time the carriage C reaches its elevated position the front end or lower end of the section 20 of the ram will have reached the rear end or upper end of the extensible section 21 of the ram. Thereafter, the operator moves the latch 25 into the position shown in Figures 3 and 4, so as to lock the two sections of the ram together, and after said sections have been locked he withdraws the bolt or holding device 26 so as to release the extensible section of the ram from the supporting structure A. The next operation is to move the carriage C downwardly on the track B, or towards the retorts, so as to cause the head on the ram to travel through the front end half of the retort and discharge the material from same. After the material has been discharged from the retort the carriage C is moved upwardly on its track, thus withdrawing from the retort the section 20 of the ram and arranging the member 27 on the upper end of the extensible section 20 of the ram in proximity to the upper bolt or holding device 26 on the supporting structure A. To telescope the ram or retract the section 21 it is necessary for the operator to first trip the latch 25 and then move the holding device 26 into engagement with the member 27 on the extensible section of the ram so as to lock said extensible section to the supporting structure A. Thereafter, the carriage C is moved downwardly on its track, and when said carriage reaches its lowermost position, as shown in broken lines in Figure 1, the latch 24 is actuated so as to move said latch into engagement with the part 23 on the extensible section of the ram and the holding bolt 26 is then withdrawn so as to release said extensible section from the supporting structure A of the apparatus. Thereafter, the carriage C is moved upwardly to its elevated position, thus causing the ram to be withdrawn from the retort.

One desirable feature of a retort discharging apparatus of the construction above described is that the operating mechanism which causes the ram to move into and out of the retort is mounted on a part of the supporting structure of the apparatus which is stationary with respect to the ram. Accordingly, such an apparatus can be made much lighter than an apparatus in which the operating mechanism for moving the ram into and out of the retorts is carried by a part of the apparatus which is raised or lowered when the elevation of the ram is changed. Another desirable feature of such an apparatus is that the operator in charge of same can be stationed on the floor at the rear of the retort bench instead of on a vertically movable part of the apparatus. Moreover, such an apparatus can be

operated easily by hand power, and it can be used successfully for dislodging or discharging material from long, open-ended retorts arranged either horizontally or inclined.

Having thus described my invention, what I claim as new and desire to secure by Letters Patent, is:

1. A retort discharging apparatus, comprising a supporting structure, a reciprocating carriage on said supporting structure provided with a rigid ram that is adapted to move into and out of a retort when the carriage moves in opposite directions, means for enabling said ram to be raised and lowered with relation to said carriage, and an operating mechanism for said carriage carried by said supporting structure. 70

2. A retort discharging apparatus, comprising a supporting structure, a stationary track on said supporting structure arranged in parallel relation to the longitudinal axes of the retorts with which the apparatus is used, a reciprocating carriage on said track provided with a vertically-disposed guiding means, and a vertically-movable member combined with said guiding means and provided with a pusher that is adapted to move endwise into one end of a retort when said carriage moves longitudinally of its track in one direction and discharge the material in said retort through the opposite end of same. 80

3. A retort discharging apparatus, comprising a supporting structure, a reciprocating carriage on said structure arranged to move in a direction substantially parallel to the longitudinal axes of the retorts with which the apparatus is used, a rigid ram carried by said carriage and adapted to enter one end of a retort and move longitudinally of same so as to discharge the contents of the retort through the opposite end of the retort, means for enabling said ram to be raised and lowered with relation to said carriage without destroying the parallel relationship between said carriage and ram, and an operating mechanism for said carriage mounted on said supporting structure. 100

4. A retort discharging apparatus, comprising a supporting structure, a reciprocating carriage on said supporting structure arranged to move in a direction substantially parallel to the longitudinal axes of the retorts with which the apparatus is used, a depending frame on said carriage, and a vertically-movable member in said frame provided with a ram that is adapted to enter one end of a retort and move longitudinally of same so as to discharge the contents of the retort through the opposite end of same. 115

5. A retort discharging apparatus, comprising a supporting structure, a reciprocating carriage on said supporting structure arranged to move in a direction substantially parallel to the longitudinal axes of the re- 120

torts with which the apparatus is used, and a vertically-adjustable, counter-balanced ram on said carriage, that is adapted to enter one end of a retort and discharge the contents of the retort through the opposite end of the retort when said carriage moves in one direction.

6. A retort discharging apparatus, comprising a supporting structure, a reciprocating carriage on said supporting structure provided with a rigid ram that is adapted to enter and move longitudinally through a retort when said carriage travels in one direction, and a counter-weighted operating mechanism for actuating said carriage and ram.

7. A retort discharging apparatus, comprising a supporting structure, a reciprocating carriage on said supporting structure that is adapted to be moved in opposite directions, a ram that is adapted to enter one end of a retort and discharge the contents of the retort through the opposite end of same, a vertically-adjustable member on said carriage which carries said ram, and a counterbalance combined with said member for holding the ram in horizontal alignment with the tier of retorts being operated on.

8. A discharging apparatus for retorts, comprising a supporting structure, a stationary track on said supporting structure, a carriage on said track provided with a reciprocating ram, a winding drum mounted on said supporting structure, and a cable wound around said drum and connected to said carriage for moving said carriage in a direction to cause the ram to be inserted in or withdrawn from a retort.

9. A discharging apparatus for retorts, comprising a supporting structure, a track on said supporting structure, a carriage on said track provided with a ram, a winding drum mounted on said supporting structure, a cable wound around said drum and connected to said carriage for moving said carriage when said drum is rotated, and a counterweight mechanism combined with said drum and consisting of a cable connected to the drum and a device that causes said cable to exert pressure on said drum tending to turn the drum in one direction.

10. A discharging apparatus for inclined retorts, comprising a supporting structure, an inclined track on said supporting structure, a reciprocating carriage on said track, and a rigid ram on said carriage that is adapted to enter one end of an open-ended retort and move longitudinally through the same when said carriage moves in one direction, thereby discharging the contents of the retort through the opposite end of same.

11. A discharging apparatus for inclined retorts, comprising a supporting structure, an inclined track on said supporting structure, a carriage on said track provided with

a frame, a vertically-movable member in said frame, and a ram connected to said vertically-movable member.

12. A discharging apparatus for inclined retorts, comprising a supporting structure, an inclined track on said supporting structure, a carriage on said track provided with a guideway, a vertically-movable member in said guideway, a ram connected to said vertically-movable member, an operating mechanism for said carriage carried by said supporting structure, and a counterbalance combined with the vertically-movable member that carries the ram.

13. A discharging apparatus for inclined retorts, comprising a supporting structure, an inclined track on said supporting structure, a carriage on said track, a pusher carried by said carriage, means for enabling the elevation of said pusher to be changed, and an operating means for said carriage comprising a cable connected to the opposite ends of the carriage, sheaves at the ends of said track over which said cable passes, and a winding drum on said supporting structure around which said cable extends.

14. A discharging apparatus for inclined retorts, comprising a supporting structure, an inclined track on said supporting structure, a carriage on said track, a vertically-disposed frame projecting downwardly from said carriage, a vertically-movable member slidably mounted in said frame, a ram connected to said member, an operating mechanism for said carriage carried by said supporting structure, and a balancing device combined with said ram for the purpose described.

15. A discharging apparatus for open-ended retorts, comprising a reciprocating carriage, a ram comprising two portions, one of which can be moved relatively to the other to increase the length of the ram, and means for locking the extensible portion of the ram in its extended and retracted positions.

16. A retort discharging apparatus, comprising a carriage, a ram carried by said carriage and comprising two portions that are arranged in telescopic relation during the first part of the discharging operation, and means for holding one portion of the ram stationary with respect to the other portion when the carriage is moved in a direction either to increase or decrease the length of the ram.

17. A discharging apparatus for retorts, comprising a carriage, a ram carried by said carriage and comprising two portions arranged in telescopic relation, means for locking said portions together when the carriage is moved in the direction to introduce the ram into one end of a retort, means for holding one section of the ram at rest when the carriage is moved in the opposite direc-

tion, thereby causing the length of the ram to be increased, and means for locking the two sections of the ram together so as to prevent the ram from collapsing when the carriage is thereafter moved in the opposite direction to complete the discharging operation.

18. A discharging apparatus for open-ended retorts, comprising a supporting structure, a carriage on said supporting structure, a ram carried by said carriage and consisting of two portions arranged in telescopic relation, latches for holding the two portions of the ram either in their collapsed or extended condition, and means for connecting the extensible portion of the ram to said supporting structure when the carriage is moved in a direction either to increase or decrease the length of the ram.

19. A discharging apparatus for retorts, comprising a shiftable supporting structure, a track on said supporting structure, a reciprocating carriage on said track provided with a depending guide, a vertically-movable member combined with said guide, a ram carried by said member and comprising an extensible portion, means for holding the extensible portion of the ram in its extended and retracted positions, and an operating mechanism for said carriage carried by said supporting structure for moving said carriage in a direction to cause said ram to enter one end of an open-ended retort and move longitudinally of same, thereby causing the contents of the retort to be discharged from the opposite end of the retort.

SILAS B. RUSSELL.
